UNITED STATES PATENT OFFICE.

WILLIAM H. ELLIOT, OF NEW YORK, N. Y.

MAGAZINE FIRE-ARM.

SPECIFICATION forming part of Letters Patent No. 225,750, dated March 23, 1880.

Application filed November 26, 1879.

To all whom it may concern:

Be it known that I, WM. H. ELLIOT, of the city and State of New York, have invented a new and Improved Magazine Fire-Arm, of which the following is a specification.

The object and nature of my invention are described as follows: The object of my invention is to provide a more convenient, simpler, and more practical magazine fire-arm than any now in use; and the nature of my invention consists in the use of certain appliances and methods which are fully set forth in the following specification and claims.

Figure 1 in the drawings is a vertical longitudinal section of my improved arm, showing the bolt and some of the smaller parts in elevation. Fig. 2 is an elevation of the same, showing the stock in vertical section. Fig. 3 is a top view of the receiver. Fig. 4 is an elevation of the connecting-rod. Fig. 5 is a side elevation of the feed-pawls. Fig. 6 is a side elevation of the connecting-link. Fig. 7 is a side elevation of the feed-lever. Fig. 8 is a side elevation of the cut-off. Fig. 9 is a side elevation of pivoted feed-pawls. Fig. 10 is a vertical section of the forward end of the bolt, showing the ejector in elevation. Fig. 11 is a vertical cross-section of a double magazine-tube adapted to contain two lines of cartridges. Fig. 12 is a section of the magazine at broken lines *w*, Fig. 1. Fig. 13 is an elevation of the mouths of the magazine, showing the head of a cartridge in section and also a ball in it. Fig. 14 is a top view of pivoted feed-pawls. Fig. 15 is a vertical cross-section of the receiver at broken lines *w'*, Fig. 1. Fig. 16 is a vertical longitudinal section of the extractor. Fig. 17 is an elevation of the forward end of the extractor. Fig. 18 is a top view of a portion of the bolt, showing the extractor.

a is the receiver, into the forward end of which the barrel *b* is screwed. *a'* is that portion of the receiver into which the magazine-tubes *a''* are fastened; *a'''*, mouth of the magazine; *b'*, chamber of the barrel; *b''*, cartridges; *b'''*, followers; *c*, bolt or breech-block; *c'*, handle of the same; *c''*, groove in the side of the bolt; *c'''*, dovetailed groove cut partly around the bolt; *d*, receiving-chamber; *d'*, opening to the same for the escape of shells; *d''*, opening for cartridges from the magazine; *d'''*, slot and recoil-shoulder for the bolt-handle; *e*, hammer-rod; *e'*, head of the same; *e''*, point of the

same; *f*, ejector-spring; *f'*, magazine-spring; *f''*, connecting-rod springs; *g*, carrier; *g'*, crank of the same; *g''*, pivot of the same; *g'''*, recess to receive the ball; *h*, connecting-rod; *h'*, crank-pin and slots, by which it is joined to crank *g'*; *h''*, pivot joining it to feed-lever *i*; *i'*, pivot or fulcrum of lever *i*; *i''*, pivot joining lever *i* to link *m*; *m'*, pin in cut-off lever *n*, which raises and lowers the rear end of the link; *m''*, pins or stops on the followers; *n'*, pivot of lever *n*; *n''*, recesses for holding lever *n* in the several positions; *n'''*, point on the free end of lever *n* which drops into the recesses *n''*; *o*, spring-pawls for feeding the cartridges; *o'*, screw for fastening the same; *o''*, bent ends of the same; *o'''*, points on the same for holding the cartridges; *p*, pivoted pawls; *p'*, pivot for holding the same; *p''*, bent ends of the same; *p'''*, points on the same for holding the cartridges; *r*, ejector; *r'*, point of the same; *s*, extractor; *s'*, hook or point of the same; *s''*, dovetailed tenon on the same which works in groove *c'''*; *u*, trigger; *u'*, point or projection on the same; *u''*, pivot of the trigger; *v*, connecting-bar across the top of the receiver.

The inventions herein described are improvements upon the arm secured to me by patent dated August 12, 1879, to which special reference is made.

The methods and devices herein shown for operating the arm and feeding the cartridges from the magazine into the receiving-chamber will work equally well in connection with a magazine of one or more tubes arranged under the barrel, or with two tubes arranged side by side in the butt-stock.

To remove the carrier for the purpose of charging the magazine, raise the forward end of the connecting-rod *h*, when the crank-pin will leave its bearings in the rod and pass into the slot *h'*. This disengages the carrier from the connecting-rod and allows it to assume the position shown by broken lines, Fig. 1. While in this position the cartridges may readily be passed into the magazine through the lower side of the arm and behind the carrier, or the magazine may be charged through the lower side of the arm and under the carrier, when the bolt is drawn back and the carrier raised without detaching it from the connecting-rod, if desired.

It is not necessary that the particular form

of connection shown should be used between the bolt and carrier. An arm extending forward from the lever *i* and connected with a crank or lever extending back from the carrier *g* will serve the same purpose.

- To facilitate the passage of cartridges into the magazine and from the magazine to the receiving-chamber, I bevel or flare the mouth of it so that it resembles somewhat the seat of a puppet-valve, as shown in Figs. 1 and 13. In a magazine composed of two tubes or two lines of cartridges, one arranged over the other, it is exceedingly difficult to guide cartridges to the inner or upper tube by the fingers alone without the assistance of this bevel; besides, the head of the cartridge being the last to leave the magazine, and the inclination of the carrier being to the rear and downward, cartridges in being raised from the lower half would, without the bevel, catch in the upper half of the magazine. The bevel operates to guide the cartridges into the magazine and to prevent the heads from catching when they are raised by the carrier.
- The magazine is composed of a single sheet of metal having a flat form, as shown in Fig. 11. The two edges of the sheet are brought together at one of the flat sides, bent inward at right angles, and soldered or brazed. The two edges bent inward form a partition between the upper and lower halves of the magazine. They also form a groove for the stop-pins *m* to work in. The side of the magazine opposite to the joint may be curved inward, as shown by broken lines, Fig. 11.

- Each half of the magazine is provided with independent cartridge-propelling devices, which operate upon the two lines of cartridges the same as if they were in separate tubes. As the cartridges are pushed into the magazine their heads are caught by the points *o* of the spring-pawls *o*, which are shown in Figs. 2 and 5.

- Both the feed-pawls *o* and the carrier *g* are operated by their connection with lever *i*, which in turn receives its oscillating movement from the reciprocating movement of the bolt. This lever has its fulcrum at *i'*, at which point it is pivoted to the receiver. At its upper end it is bent at right angles, and projects into groove *e* in the bolt. The shoulders at each end of the groove, coming in contact with the bent end of the lever, give to that device the necessary oscillating movement.

- To the lower end of the lever the forward end of the link *m* is pivoted at *i''*. The rear end of link *m* is controlled by cut-off lever *n*, which is pivoted to the receiver at *n'*. The connection of link *m* with lever *n* is by means of pin *m'* in the lever working in a slot in the rear end of the link.

- The upper end of lever *n* has a projection, *n''*, which drops into the recesses *w*, and by that means holds this lever in its several positions. In the drawings it is represented in

its central position, in which case it directs the point of the link against the central feed-pawl only; but when the point *n''* is in the rear recess it directs the rear end or point of the link at both the central and lower feed-pawl; when in the forward recess it directs the point of the link at both the central and upper feed-pawl.

The forward ends of the upper and lower pawls are bent outward, so that the point of the link passes under them, raising their points to release the cartridges, while the forward end of the central feed-pawl is bent inward, so that the point of the link passes over it, so forcing its point down in the rear of the heads of the first two cartridges, in which position it prevents the second cartridge from passing out of the magazine when the first is released.

The lever *i* may be dispensed with, and a slide provided with the bent end used instead. To this slide both the link *m* and the connection *h* would be attached, and move back and forth with it.

To feed cartridges from the lower half of the magazine, the point *n''* has to be moved to the rear recess, *n'*. Now, when the bolt is moved forward to close the arm, the upper end of lever *i* is carried forward, the carrier, by means of connecting-rod *h*, is brought to the position shown at *g*, Fig. 1, and the link *m* is carried backward, its point first depressing the central pawl to its full depth, then raising the lower pawl and releasing a cartridge, which is immediately pushed forward by the magazine-spring until the ball is lodged in recess *g''*, directly under the forward end of the bolt, the bolt and carrier serving as guides to this end for cartridges from either half of the magazine. By this movement of the cartridges the head of the second one is caught by the point of the central pawl. While the parts are in this position, with one cartridge in the chamber of the barrel and another resting on the carrier, the arm is fired.

On opening the arm a full backward movement of the bolt brings the lever *i* and carrier *g* to the position shown in Fig. 2, raising the cartridge that was resting upon the carrier into the receiving-chamber, and withdrawing the point of the link *m* from between the bent ends of the central and lower pawl. By this movement the link *m* first allows the point of the lower pawl to enter the tube to the full depth; then, continuing its motion, it allows the central pawl to release the next cartridge, which moves forward a little and is caught upon the point of the lower pawl, when the parts are ready for a repetition of the operation.

To feed cartridges from the upper half of the magazine, the point *n''* has to be moved to the forward recess, *n'*, which presents the point of link *m* to the central and upper feed-pawl, the manipulation being the same in both cases.

The spring-pawls are so formed that the upper and lower ones, when left to themselves,

catch the heads of the cartridges in the magazine, while the central pawl only catches the cartridges when forced down by the link m . One valuable feature in this method of feeding the cartridges forward is in the order in which the points of the several pawls are moved. In the backward movement of the link the point of the central pawl is first depressed to its full depth to catch the second cartridge before the first is liberated; and in reversing the operation the points of the upper and lower pawls are permitted to enter the magazine to the full depth before the point of the central pawl releases the second cartridge.

To facilitate the carrying of the head of a cartridge from the lower half of the magazine past the ball of the first cartridge in the upper half, it is necessary that the cartridges in the upper half be stopped farther back than those in the lower half, as shown in Figs. 1 and 2.

The knob on the cut-off lever n , opposite the point n''' , is intended to come to the outer surface of the arm for convenience of manipulation; but this particular method of controlling the link is not essential. Any of the well-known methods of effecting the cut-off may be substitutes for it.

In Figs. 9 and 14 I have shown a modification of the spring-pawls. They have the same points. They have bent ends, by which they are operated; but they are pivoted to the receiver, and each has a separate spring, instead of the spring and pawl being made in one piece.

The resistance offered by the central feed-pawl to the backward movement of the link holds all the small parts, including the carrier, stationary in the position shown in Fig. 2 while the bolt is being pushed forward to close the arm.

For extracting the empty shell I employ extractor s , Figs. 16, 17, and 18. This device is composed of three parts—a bar, s , (shown in section, Fig. 16,) a head, s' , consisting of a flat band which is curved partly around the end of the bolt, having the usual hook at one end, and attached at its middle to the forward end of the bar, (shown in elevation, Fig. 17,) and a dovetailed tenon, s'' , on its rear end, which attaches the extractor to the bolt by means of a dovetailed groove, e''' , which is cut partly around the bolt. This extractor slides in a groove cut in the under side of that portion of the receiver which covers the receiving-chamber, as seen at s''' , Figs. 3 and 15. The middle of the upper side of the bar touches the bottom of the groove and affords the necessary elasticity to enable the hook to pass over the rim or head of the cartridge. The band also has some elasticity, and so yields a little for that purpose.

When the reciprocating movement is given to the bolt the extractor moves with it, being attached by the tenon and groove; but when the oscillating movement is given to the bolt

the extractor is held stationary by the groove s''' , the tenon s'' sliding around the bolt in the groove e''' .

A stop may be put in the groove e''' to prevent the extractor from becoming detached from the bolt while the bolt is detached from the arm for the purpose of cleaning.

To eject the shell from the receiving-chamber, I employ ejector r . (Shown in Figs. 10 and 18.) This device is composed of two parts—a round bar which has a longitudinal movement in the forward end of the bolt, projecting out of the same at r' , and an elongated head extending into the interior of the bolt, through which the point of the hammer-rod passes and upon which the ejector-spring rests. This spring forces the point r' out of the bolt, as shown.

On closing the arm with a cartridge in the chamber of the barrel, the head of the cartridge forces the ejector back, depressing the spring until the hook of the extractor takes hold of the rim of the cartridge. On opening the arm the hook of the extractor holds the head of the cartridge close against the bolt, keeping the ejector back, the chamber of the barrel acting as a retainer until the forward end of the shell is free, when, by the action of the ejector-spring, the shell is thrown out of the receiving-chamber.

Should the ejector-spring from any cause fail, the operation of the ejector is rendered positive by the arrangement of the parts as shown in Fig. 1, where it may be seen that the head of the ejector forms the shoulder at the forward end of the groove e'' , so that without the spring the ejector would be thrust forward by coming in contact with the bent end of the feed-lever t .

It is desirable that the shell be expelled from the receiving-chamber as early during the backward movement of the bolt as possible, so that it may be out of the way of the next cartridge. This is necessary in all magazine-arms where the opening to the receiving-chamber is at the side of the receiver, or where the form of the receiver is such as to prevent the advancing cartridge from lifting the shell of the previous cartridge out of the way.

By reference to Fig. 3 it may be seen that the opening to the receiving-chamber d' and the slot and shoulder d''' are divided by a bar, n , and that the receiving-chamber extends back under this bar, so that when the arm is operated rapidly the heads of the cartridges are thrown up against the under side of the bar, which prevents them from being thrown out of the receiver by the carrier. The bar adds considerable strength to the receiver, and also prevents the receiver from springing when case-hardened.

By reference to Fig. 1 it may be seen that the forward end of the magazine is contracted or reduced in its vertical diameter. Fig. 12 represents the diameter at broken lines w , Fig. 1, just back of the contraction, while Fig. 13

represents the size of the contracted part of the magazine. Broken lines in the latter figure show the amount of contraction.

Whether the carrier be operated by positive movement or by spring-power, reducing the size of the mouth of the magazine has several advantages. It compacts the arm, it presents the cartridges to the carrier in a more exact and uniform manner, it assists in directing the cartridges into the recess g'' , and the carrier, having less movement, handles the cartridges with less violence and in every way better. It is only necessary that there should be room enough in the mouth of the magazine for one head and one ball, as shown in Fig. 13, as there never can be two heads in it at the same time. This peculiar feature of the magazine is the result of turning or bending the mouth of each tube or cartridge-space toward the other, so that, instead of each tube having an independent mouth, the two mouths are combined to produce one wide mouth of sufficient capacity to allow the free passage of a cartridge through it from one tube, while at the same time it holds the ball end of the first cartridge in the other tube; and these advantages are obtained by the manner in which the mouths of the two passages are conjoined without making said mouths, or any part of them, movable for that purpose.

In charging a magazine which has two lines of cartridges arranged one over the other in the butt-stock, particularly where the upper line of cartridges is stopped farther back than the lower line, it is very difficult to enter cartridges into the upper half of the magazine behind the ball or follower projecting from the lower half. To remove this difficulty I employ point or catch u' on the trigger. After the lower half of the magazine has been filled the cartridges in that line are forced back, when, by pressure on the trigger, the first cartridge is caught by the head on the point u' , and the whole line thereby held back until the upper half of the magazine has been charged.

A carrier properly constructed and pivoted under the rear end of the barrel, as shown in Fig. 1, but operated by a spring, as represented in my patent before mentioned, will work as practically as the one herein shown.

Having described my invention, what I desire to have secured to me by Letters Patent of the United States is—

1. In a magazine fire-arm, a magazine adapted to contain two lines of cartridges in the butt-stock, arranged one over the other, and having the mouths of the cartridge-spaces or tubes conjoined, as shown, in combination with carrier g , pivoted to the receiver below the receiving-chamber and moving in a plane parallel with the plane of the two axes of the tubes, whereby a cartridge may be delivered with uniformity and accuracy upon the carrier from each of the mouths so conjoined alter-

nately, if desired, without change in the position of the parts of the same and without interference with the cartridge passing from one mouth by the cartridge resting in the other mouth, substantially as specified. 70

2. In a fire-arm, an extractor composed of bar s , circular elastic head s' , and tenon s'' , adapted to slide longitudinally in groove s''' , and arranged directly over the receiving-chamber, in combination with bolt c , having both a reciprocating and an oscillating movement, substantially as shown and described. 75

3. In a magazine fire-arm having its magazine in the butt-stock, the combination of the reciprocating and oscillating bolt c , provided with groove c'' , feed-lever i , pivoted to the receiver and projecting into said groove at its upper end, connection h , pivoted at its rear end to lever i and at its forward end to carrier g , said carrier being pivoted to the receiver under or nearly under the rear end of the barrel, substantially as specified. 80 85

4. In a magazine fire-arm, the combination of the detachable connection h , pivoted at its rear end to feed-lever i , and joined at its forward end, by means of the crank-pin and slot h' , to the crank g' of the carrier, said carrier being pivoted under or nearly under the rear end of the barrel, whereby the carrier may be 90 released from the connection h for the purpose of charging the magazine, substantially as specified. 95

5. In a magazine fire-arm having its magazine in the butt-stock, the combination of the reciprocating and oscillating bolt c , provided with the groove c'' , feed-lever i , pivoted to the receiver and projecting at its upper end into said groove, and link m , pivoted at its forward end to lever i , and at its rear end adapted to operate upon the bent ends o'' of the pawls o , said pawls being fastened to the side of the receiver over the cartridge-spaces, and provided each with a point, o''' , for stopping the cartridges, substantially as and for the purpose specified. 100 105 110

6. In a magazine fire-arm, a double tubular magazine composed of a single sheet of metal, the edges of the sheet meeting at the middle of one of the flat sides and bent inward at right angles, and soldered or otherwise fastened, whereby a partition is formed between the two lines of cartridges, and also a groove provided within the magazine for the stoppin to work in, substantially as shown and described. 115 120

7. In a magazine fire-arm, the bolt c , lever i , and link m , in combination with the feed-pawls o , having their bent ends constructed and arranged as shown in relation to said link, 125 whereby the several parts operate upon the cartridges in the order substantially as specified.
